UNDERFEED STOKER

Richard Zinkernagel, New York, and George P. Jackson, Flushing, N. Y., assignors to Combustion Engineering Company, Inc., New York, N. Y.

Application January 14, 1936, Serial No. 59,046

7 Claims. (Cl. 110—44)

This invention relates to stokers and particularly to the multiple retort underfeed type.

The invention contemplates, in a multiple retort stoker, a novel assembly of parts so arranged as to cooperate to effect efficient combustion of the fuel thereon, which parts do not interfere with each other's individual functioning.

An object of the invention is to provide a common pusher actuating means for each retort cooperating with individual pusher control means, said control means being independent in control from said actuating means.

A second object of the invention is to provide a novel controlling means for the common pusher actuating means for each retort as well as for the individual pushers.

Another object of the invention is to provide a novel pusher construction.

Another object is to provide cooling means of the structural supporting means of the tuyères and retorts.

A further object of the invention is to provide a novel and simple means for the orientation of the major stoker parts during their assembly, said orienting means serving as major supporting and orienting structure for said major stoker parts.

Still another object of the invention is to provide an overfeed section construction adapted to minimize clinker formation.

How the foregoing, together with such other objects and advantages as may hereinafter appear, or are incident to our invention, are realized, is illustrated in preferred form in the accompanying drawings, wherein:

Fig. 1 is a longitudinal sectional view of a stoker constructed in accordance with the invention;

Fig. 2 is an enlarged, partly sectional, view of the forward end of the stoker showing the arrangement of the orienting beams and also the common adjusting control for operating the pushers of a retort;

Figs. 3 and 4 are sectional views on the lines 3—3 and 4—4 in Fig. 2 and illustrate the construction of the common adjusting control for the pushers of a retort;

Fig. 5 is an elevational view of the orienting beams for the retorts as seen from the right hand side of Fig. 2, some parts being omitted and others shown in section to illustrate details of construction;

Fig. 6 is an enlarged side elevational view of the forward portion of a retort and tuyère as viewed along lines 6—6 in Fig. 7;

Fig. 7 is a sectional view on the line 7—7 in Fig. 6, partly broken away showing the construction of the retorts and tuyères;

Fig. 7A is a sectional view taken on the line 7A—7A in Fig. 7;

Fig. 8 is a side elevational view, partly in section, of the overfeed section located beyond the retort illustrated in Fig. 6, and shows the control means for variably regulating the operation of the moving grate bars;

Fig. 9 is an end view, partly sectioned on line 9—9 of Fig. 8, of the overfeed section;

Fig. 10 is a plan view, partly in section, showing the construction of the auxiliary rams or pushers; and

Fig. 11 is a sectional view along line 11—11 in Fig. 10 illustrating the individual controls for regulating the movement of the pushers and also showing the construction of the latter.

Referring to the drawings, the numeral 1 designates one of a plurality of columns spaced at suitable intervals across the width of the stoker and supporting the main beams 2 and 3 which run transversely of the stoker. In the arrangement shown, the beam 2 is a channel beam lying in a vertical position and forming part of the front wall of the stoker. The beam 3 is an I-beam mounted horizontally near the top of beam 2 so that the meeting flanges of the beams form right-angle surfaces 2a, 3a that serve as an orientation means for the major parts of the stoker. Fastened on top of beam 2 and also to beam 3 are face plates 4 having cast integral therewith the main ram cylinders 5, there being one face plate for each retort of the stoker. Ram box sides 6 are bolted at right angles to the face plates 4 and have secured thereto the forward ends of beams 7 which at their rear ends rest freely in saddles 8 carried by the rear main supporting beam 9, Fig. 8, thereby providing for freedom of expansion and contraction. The beams 7 form the main longitudinal supports for the tuyères and adjoining retorts and also for parts auxiliary thereto, as will be apparent as the description proceeds. The orientation of the beams 7 by attachment to the ram box sides 6 which in turn are oriented by being secured to the face plates 4 that are fitted to the right-angled surfaces 2a, 3a formed by the beams 2, 3 results in the upper end faces of the beams 7 being located in the same plane so that these beams are parallel and thus enables all of the parts of the alternating retort and tuyère sections of the stoker to be simply and accurately oriented with relation to each other.

The beams 7 are of box girder construction and constitute air boxes for the superposed tuyères, the beams being reticulated on their upper and lower faces to provide for the passage of air into the tuyères from the air chamber 10 beneath the stoker. Sectional side plates 11 for the retorts and tuyères are secured to the beams 7 as by bolts 12. The plates 11 are spaced from the beams to provide air gaps 13 between the sides 10 of the beams and the plates. The side plates 11 rest upon beams 7 at intervals, as by feet 14, leaving air spaces 15 between the feet 14. Air may pass from the chamber 10 beneath the stoker around the air boxes 12a below the tuyère blocks 15 through the air gaps 13 and spaces 15 and into the tuyères at all times, that is at banking periods when the air dampers to the tuyères are closed as well as during other periods. Thus, the beams 7 are cooled on both sides by the incoming air for combustion during all periods of operation and are thereby protected from overheating.

The space at the bottom of each retort between its side plates 11 is spanned at intervals longitudinally thereof by supporting plates 20 on which ride the auxiliary rams or pushers 21, in this case four in number. The plates 20 are yieldingly fastened to the bottom flanges of the side plates 11 to allow movement for expansion that may occur. The pushers 21 are adjustably connected, for selectively regulating their stroke, as will be described later, to individual brackets 22 all fixed to a rearwardly inclined reciprocable beam 40, except the forwardmost pusher 21, which as shown in Fig. 2, is carried by rod 74 connected to the forward end of beam 40 for actuating the latter. Rod 74 and beam 40 together constitute a pusher bar for reciprocating the pushers and the sliding grate bars 51. Beam 40 is fixed at intervals to plate members 41 formed with trunnions 41a provided with rollers 42 guided between upper and lower tracks 43, 44 supported by brackets 45 depending from the longitudinal beams 7.

The overfeed section of the stoker comprises alternated fixed and moving grate bars 50, 51, respectively, the latter having slots 52, engaging a transverse rail 53. These bars may be either solid or of hollow construction. Similarly to pushers 21, the operating stroke of rail 53 and hence of bars 51, is variable as will be set forth later. The reciprocating movement of these bars is effected in one direction through a member 54 operatively connected to the reciprocable beam 40 and in the other direction by means of a rod 55 fixedly connected at one end to the beam.

The main ram 60, the auxiliary rams or pushers 21 and the grate bars 51 of each retort receive their motion indirectly from a crank shaft 60 driven by any suitable means, as a system of selective reduction gears, which in turn are driven by a motor. The ram 60 is driven by the usual crank and crank pin 61 through a connecting rod 62 carrying a wrist pin 63 for actuating the ram. Crank pin 61 also operates a bell crank 66 through a connecting rod 67, a pin and slot connection 68, 69 between these parts providing lost motion and reducing the amplitude of motion imparted to the bell crank 66.

Bell crank 66 carries a pin 70 extending into slots 71 in the bifurcations of a clevis 72 mounted on the outer end of a rod 74. Rod 74 extends through a bearing and air seal 80 in beam 2 and is connected to transmit motion to the beam 40 which together with rod 74 constitutes a common

pusher bar for the four pushers 21 and the alternate, sliding grate bars 51 corresponding to the related retort.

The operating stroke of the pushers and grate bars have a common adjustment comprising a multi-step cam 75, fixed to a shaft 73 extending parallel to the rod 74. Shaft 73 is positioned close to the push rod so that part of cam 75 is always in the path of movement of pin 70. On rotation of cam 75 its steps 76 may be selectively interposed between the head of rod 74 and the pin 70 mounted in a link 70a pivotally carried by bell crank 66 that operates the rod to vary the amount of movement imparted to rod 74 from the ram. Cam 75 is adjusted from the front of the stoker by a hand wheel 77 indexed to correspond with the steps of the cam. The motion of hand wheel 77 is transmitted to cam 75 through shaft 73 which has a telescopic section 73a formed with a slot 73b in which a stud 73s is engaged so as to permit reciprocating movement of cam 75 with rod 74 while providing for rotative adjustment of the cam by hand-wheel 77. The reciprocating part of shaft 73 is supported by a bracket 78 as shown in Fig. 3. Thus, by adjusting cam 75 to selectively position the steps thereof to take up more or less of the amount of lost motion permitted by the slots 71 in clevis 72 before pin 70 is effective to advance the rod 74, the extent of rearward movement imparted to rod 74 and beam 40 for advancing the pushers 21 and grate bars 51 may be varied. The pusher bar 74, 40, and hence the pushers and grate bars, are returned forwardly to their starting positions by pin 70 on bell crank 66 engaging links 72 at the forward end of the slots 71.

Each pusher 21 comprises a skeleton cradle 23 which lies below the two upper plate castings 24, 25 constituting the two steps of the pusher which advance the fuel down the stoker. At either side 40 of cradle 23 and below plates 24, 25 are pusher side plates 26 which are independently free to move sideways and are held against the retort sides 11 by means such as springs 27 thereby preventing the passage of siftings between the pusher and retort sides. The plates 24, 25 are removable for replacement and interlock with side plates 26 at 28 and with each other at 29. The side plates 26 in turn interlock with cradle 23 and are moved thereby back and forth. A cam 30 (Figs. 10 and 11) is mounted on a shaft 31 carried by the related bracket 22 on the reciprocable actuating beam 40 which constitutes the pusher bar. Cam 30 has stepped surfaces 32, four steps in this instance, any one of which may be placed in position to contact and push cradle 23 forwardly by revolving the cam into position manually through the respective indexed hand wheel 33 and shaft 31. The different steps provide a variable lost motion between the cam 30 and cradle 23 and, consequently, a variable stroke of the pusher. The return stroke is caused by bracket 22 engaging the hook 34 on bolt 35, the bolt in turn drawing the cradle 23 forward by its collar 36 engaging a shoulder of the cradle provided therefor. Cradle 23 is formed with a vertical slot 37 and when bolt 35 is revolved through about 180 deg., hook 34 will be in a position where it will pass through said slot when the bolt is withdrawn. Likewise, hook 34 will pass through the slot in bracket 22 so that with the release of the bolt the cradle may be drawn to the right Fig. 11 and the entire pusher 21 with it and free from beneath the pusher supporting plates 20 for the pusher above. The 75

step plates 24, 25 of the pusher may then be removed by revolving the top plate 24 slightly clockwise around the rearward end of bolt 35 and lifting it rearwardly clear, and then lifting off the plate 25 which forms the lower step. Cradle 23 may then be removed if necessary as well as side plates 26. By these novel means the pusher parts may be easily renewed from the furnace side, of the stoker. Suitable seals are provided 10 at the front edge of the pusher to reduce the siftings and air leakage which would otherwise pass by.

The different steps of each cam 30 provide a variable lost motion between beam 40, bracket 22 thereon and the related pusher cradle 23 and consequently enable the stroke of each pusher 21 to be variably regulated independently of that of the others although all receive their motion from the main rod 74 and beam 40 common thereto.

The member 54 for reciprocating the alternate movable grate bars 51 is guided in a bearing 56 and at its forward end is selectively engageable by the steps of a cam 57 similar to the cams 30 for the pushers 21. Cam 57 is rotatable by a shaft 58 operated from a hand wheel at the front of the stoker. Thus, the cam steps which are positioned at different distances from the forward end of member 54 may be selectively aligned 30 therewith so that the travel of the movable grate bars 51 may be varied as in the case of the pushers 21. The rod 55 connected to and moving with beam 40 is provided with adjustably positioned nuts 59 engageable with the rear end of member 54 for returning rail 53 and hence the grate bars 51 on the forward stroke, the adjustability of nuts 59 permitting a lost motion in the stroke.

The overfeed section of the present stoker moves each alternate grate bar. It has been found that greater agitation of fuel results, with resultant avoidance of clinker adhesion and a better air distribution with better burning. The difficulty of adjacent parallel movements of 45 groups of bars involving a considerable area is completely avoided. It has been found that there is a more uniform transition of fuel flow from the retorts to the overfeed section and a more uniform flow of fuel across the overfeed section. 50 The clinker adhesion that occurs in the group movement does not occur with this new overfeed section.

The shafts 31, 58 for adjusting the stroke regulating cams 30, 57 of the pushers 21 and reciprocable grate bars 51 all reciprocate as a unit with the rod 74 and beam 40. In order that the hand wheels on these shafts may be stationary, that is non-reciprocating, telescopic sections 31a, 58a, similar to those of shaft 73 (Fig. 3) are 60 provided to transmit the motion of the hand wheels to the shafts through lugs operating in slotted lug ways, lubrication therefor being provided through the hollow portions of the shaft. Universal joints 31u, 58u are provided for transmitting motion through angularly disposed portions of the shafts. The shafts 31, 58 are supported beneath the retorts by brackets 46 depending from beam 40, as well as by the brackets 22 thereon adjoining the pushers. As described 65 above, the beams 40 are reciprocatingly supported beneath the retort by the trolley members 41 guided on the tracks 43, 44 carried by the main longitudinal box guides 7. As shown in Fig. 2, 70 the shafts 31, 58 extend through bearings 47,

mounted on or adjacent to the main transverse beam 2, that serve as air seals.

Air for combustion enters the chamber 10 common to all the tuyères which are disposed transversely of the stoker and extend longitudinally thereof between the retorts. This chamber is limited by the stoker front which is located in alignment with the main transverse beam 2, and extends rearwardly below the rear supporting beam 9 to beneath the overfeed section of the 10 stoker. As mentioned above the longitudinally disposed box girders form air boxes for the tuyères. It may be desirable to have control dampers at the bottom of the supporting beams 14 under each tuyère whereby the air to each 15 tuyère or portion thereof is independently controlled.

The arrangement of parts of our improved stoker provides a common pusher actuating means for each retort, the stroke of which may 20 be varied, cooperating with individual and independent pusher control means for each pusher and for the overfeed grate bar control means.

What we claim is:

1. In a stoker having a retort, a plurality of 25 pushers therein, a reciprocable pusher bar connected to said pushers and a member for operating said bar; pin and slot means providing a lost motion connection between said member and said pusher bar; means for variably regulating the 30 movement imparted to said bar through said connection comprising; a shaft extending adjacent said bar and member; a cam slidably keyed to said shaft and formed with a plurality of portions varying in length in the direction of movement of said bar and adapted to be individually disposed between the said pin of said connection and said pusher bar for regulating the extent of reciprocation of the latter.

2. In a stoker having a retort comprising side 40 plates and intervening bottom plates on which pushers are reciprocable to feed fuel along the retort; a pusher in said retort comprising; a frame or cradle; stepped plates mounted on said cradle for supporting and advancing the fuel; 45 side plates freely mounted on said cradle below said stepped plates; and means carried by said cradle urging the side plates of said pusher against the side plates of said retort.

3. In a stoker having a retort comprising side 50 plates and intervening bottom plates on which pushers are reciprocable to feed fuel along the retort; a pusher in said retort comprising; a frame or cradle; stepped plates mounted on said cradle for supporting and advancing the fuel; side plates 55 freely mounted on said cradle below said stepped plates; and springs mounted transversely of said cradle and arranged to exert pressure against said pusher side plates for urging them toward the side plates of said retort.

4. In a stoker; a plurality of spaced retorts comprising side plates extending longitudinally of the stoker with intervening bottom plates adjacent the lower edges thereof in each retort; tuyère blocks supported by the adjacent side plates of contiguous retorts; beams extending longitudinally of the stoker below said blocks and disposed adjacent the lower portions of the outer sides of said side plates and spaced therefrom for providing air passages between said beams and plates; and feet at intervals on said side plates intermediate the top and bottom edges thereof resting on the tops of said beams to mount said plates thereon and providing openings along the top of said beam between said feet communi- 70 75

cating with said passages for admitting air flowing through said passages from below said retorts to the space above said beams and below said tuyère blocks for cooling the upper portions of the outer surface of said side plates.

5. In an underfeed stoker having a retort including spaced side plates extending longitudinally of the stoker and bottom plate disposed therebetween; a pusher for said retort comprising; a frame or cradle adapted to ride on said bottom plates and having a forward portion of greater height than its rear portion; a step plate mounted on the lower rear part of said cradle and having an angular portion extending downwardly over the rear side of the lower portion of said cradle; a lug or flange on the forward edge of said plate; a second step plate mounted on the upper forward part of said cradle and having an angular portion extending downwardly in front of said upper part and of the forward flange on said first plate to lock the latter on the cradle; a downwardly extending lug or flange on the forward edge of said second plate lockingly engaging the forward face of said cradle; a reciprocable push bar for actuating said pusher; a bracket on said push bar formed on its upper face with a slot extending longitudinally of the pusher; means carried by said bracket and engageable with said cradle for moving it in one direction; and a bolt extending through the angular portion of said second plate and having a lug thereon engageable with said cradle and a portion lying in the slot in said bracket with a second lug at its forward end engaging said bracket for moving said cradle in the opposite direction.
6. In an underfeed stoker having a retort including spaced side plates extending longitudinally of the stoker and bottom plates disposed therebetween; a pusher for said retort comprising a frame or cradle adapted to ride on said bottom plate and having a forward portion of greater height than its rear portion; a step plate mounted on the lower rear part of said cradle and having an angular portion extending downwardly over

the rear side of the lower portion of said cradle; a lug or flange on the forward end edge of said plate; a second step plate mounted on the upper forward end part of said cradle and having an angular portion extending downwardly in front of said upper part and of the forward end flange on said first plate to lock the latter on the cradle; a downwardly extending lug or flange on the forward end edge of said second plate lockingly engaging the forward end face of said cradle; a reciprocable push bar for actuating said pusher; a bracket on said push bar formed on its upper face with a slot extending longitudinally of the pusher; means carried by said bracket and engageable with said cradle for moving it in one direction; and a bolt extending through the angular portion of said second plate and having a lug thereon engageable with said cradle and a portion lying in the slot in said bracket with a second lug at its forward end engaging said bracket for moving said cradle in the opposite direction, said bolt being rotatable in said bracket slot for disengaging said second lug from said bracket to permit said pusher being disengaged from and moved away from said bracket.

7. In a stoker having a retort, a pusher mounted for reciprocation therein, a reciprocable pusher bar and means for actuating the latter; a bracket fixedly carried by said bar for moving said pusher rearwardly in said retort; a rotatable shaft supported by said bracket for varying the movement of said pusher; a rotatable member mounted on said shaft and interposed between said bar-carried bracket and said pusher, said member being formed with a plurality of steps symmetrically disposed about said shaft and varying in length axially of said shaft for selectively engaging said pusher on rotation of said shaft to vary the movement of said pusher by said bar; and means carried by said pusher and engageable by said bar-carried bracket for moving said pusher forwardly.

RICHARD ZINKERNAGEL.
